(57) **CLAIM**

The ornamental design for a lamp having mosaic lens, as shown and described.

(21) Appl. No.: **29/377,003**

DESCRIPTION

(22) Filed: **Oct. 15, 2010**

FIG. 1 is a perspective view of the lamp having mosaic lens of the present invention;

(51) **LOC (9) Cl.** **26-05**

FIG. 2 is a front elevation view thereof;

(52) **U.S. Cl.** **D26/67**

FIG. 3 is a rear elevation view thereof;

(58) **Field of Classification Search** D26/67-71,

D26/85, 128-135; 362/152, 153, 153.1,

362/180, 183, 431, 653

FIG. 4 is a left side elevation view thereof;

See application file for complete search history.

FIG. 5 is a right side elevation view thereof;

FIG. 6 is a bottom plan view thereof;

FIG. 7 is a top plan view thereof;

FIG. 8 is a front elevation view thereof with a ground stake shown in phantom;

FIG. 9 is a rear elevation view thereof with a ground stake shown in phantom;

FIG. 10 is a right side elevation view thereof with a ground stake shown in phantom; and,

FIG. 11 is a left side elevation view thereof with a ground stake shown in phantom.

The broken lines are shown in the views for illustrative purposes only and form no part of the claimed design.
